Atty.

UNITED STATES PATENT OFFICE.

THOMAS DALTON, OF CHICAGO, ILLINOIS.

COMBINED CIGAR-CUTTER AND MATCH-SAFE.

SPECIFICATION forming part of Letters Patent No. 439,481, dated October 28, 1890.

Application filed February 13, 1890. Serial No. 340,240. (Model.)

To all whom it may concern:

Be it known that I, THOMAS DALTON, a citizen of the United States, and a resident of Chicago, county of Cook, and State of Illinois, have invented new and useful Improvements 5 in a Combined Cigar-Cutter and Match-Safe, of which the following is a specification, reference being had to the accompanying drawings, illustrating the invention, in which—

Figure I is a top or plan view of my invention. Fig. II is a vertical central sectional elevation of Fig. I on line x ; Fig. III, an elevation of the weighted end of the pivoted knife-plate, removed from the other mechanism; Fig. IV, an elevation of the knife, looking in the direction indicated by dart z , the weighted lever to which it is attached, a portion of one side of the case, and one of the guides which keeps the knife centrally between the sides of the case.

This invention relates to an improvement in devices for cutting off the tips of cigars, and by the manipulation of the same devices preventing more than one match at a time 25 from being taken from the match-receptacle.

The nature and operation of the invention will be fully understood by the following detail description.

A B C represent the wood base, which has 30 formed therein a receptacle E to hold the cigar-tips, and a match-receptacle F, the latter being provided with a groove G below, so that the finger may be put under the matches. The metal portion consists of the sides K H L 35 and ends I N J M. The portions H I J project out beyond the other portions and in them are tapped screw-threads, in which screws (shown by dotted lines $i i i$) are turned to hold the wood and metal together. The end portion M of the case extends down to the bottom 40 of the groove G, and vertically in its central portion is formed an open slot Q, in order that the fingers may be put into the match-receptacle, the wood base being cut away at R for a like purpose. On the side portions L, at 33, are 45 formed upwardly-projecting eyes to receive the bolt S, which pivots the weighted knife-plate $a b d$ to the case. The front portion over the weight T is pitched downward and cut 50 away centrally at P to be out of the way of the fingers entering the receptacle F. Hence the weight is double, as shown at Figs. I and II.

The knife-holder consists of a metal block U, pivoted to the sides of the metal case by a bolt f , and its front end has a bearing flat against 55 the insides of the double-weighted portion when the knife and knife-plate are in position, as at Fig. II. A cigar-tip m can be inserted in the hole c or in smaller holes $e e$. On the holder U are formed two lugs or stops 60 V and x , which regulate the throw of the knife-plate by the lug X coming against the left-hand edge of bar or cross-piece W , which is a portion of the case when the knife-plate is in the position shown, and the lugs V come 65 against the opposite edge of the bar when the knife-plate is in the position shown by dotted lines, Fig. II. Cast with the metal portion of the case are inwardly-projecting guides $Y Z$, which serve as guides to hold the knife centrally 70 on the pin f . A plan of the guides is shown at Fig. I, and cross-section of one guide is shown at Fig. IV. The shank h of the knife g is slotted at p , that it may be secured to the holder U and adjusted and held by a screw. 75 The blade g is bent at an obtuse angle to the shank at a point above the top of the case, so that it may not come in contact with it. The weighted portions T T of the knife-plate are provided each with a projection O , which 80 when the weighted levers are down come upon the frame. When the levers are in this position a match can be brought up between them and the frame and to the projections T T, which will rise high enough above the 85 frame to permit but one match to be taken out at a time, there being only space for this purpose.

In practice it is found that the weighted portions serve a much better purpose for holding the knife and knife-plate in position to cut off a tip of a cigar than springs, in that the power is mostly expended in cutting off the tip and not in forcing the knife-plate down, and, as a result, dry cigars are not broken.

The knife can be taken out to be sharpened by loosening the screw under the knife-plate and then raising the front end of the holder U by inserting the finger through opening P Q. This permits the knife-plate to be raised 95 nearly perpendicular, the match-safe being opened at the same time.

What I claim, and desire to secure by Letters Patent, is—

1. In a cigar-cutter and match-safe, a two-part case divided into two compartments for separating tobacco chips from matches in the lower part, and an upper portion extending 5 into the compartments of the lower part, in combination with a knife, knife-holder, and a knife-plate which has holes for receiving the tips of cigars and is pivoted to the upper part and forked at one end, said forked portions 10 being weighted and provided with projections O O, which extend to the end plate of the case and are elevated above said plate when the knife-plate is brought to a horizontal position and the weighted forked portions of the 15 knife-plate are brought to the end plate to permit a single match to be removed at a time, as specified and shown.

2. A knife-plate forked at its rear end, the forked portion being weighted, said plate being provided with one or more holes at its front end for receiving the tip of a cigar to reach the knife and pivoted to the sides of the case, in combination with a knife-holder and a knife adjustably connected therewith, the holder being pivoted to the sides of the case 25 and provided with stops, a transverse plate on the top of the case to regulate the throw of the knife, and a compartment to receive the chips cut from the cigar, as and for the purpose specified.

THOMAS DALTON.
